J. E. GATES.

TYING DEVICE.

APPLICATION FILED OCT. 2, 1917.

1,360,920.

Patented Nov. 30, 1920.

UNITED STATES PATENT OFFICE.

JEFFERSON E. GATES, OF GAINESVILLE, FLORIDA, ASSIGNOR OF ONE-HALF TO A. R. HARPER, OF GAINESVILLE, FLORIDA.

TYING DEVICE.

1,360,920.

Specification of Letters Patent. Patented Nov. 30, 1920.

Application filed October 2, 1917. Serial No. 194,392.

To all whom it may concern:

Be it known that I, JEFFERSON E. GATES, citizen of the United States, residing at Gainesville, in the county of Alachua and State of Florida, have invented certain new and useful Improvements in Tying Devices; and I do hereby declare the following to be a full, clear, and exact description of the invention, such as will enable others skilled in the art to which it appertains to make and use the same.

This invention relates to parcel ties and has for an object to provide a new and improved tie for quickly and securely tying a parcel as for instance, a bundle of letters with the least possible number of motions and the least possible wear upon the cord employed.

A further object of the invention is to provide in a parcel tie, a device quickly adjusted to a parcel and providing means for exerting tension to the cord for tightening the parcel.

With these and other objects in view, the invention comprises certain novel constructions, combinations and arrangement of parts as will be hereinafter more fully described and claimed.

In the drawing:

30 Figure 1 is a perspective view of the initial motion and position in placing the tie upon a parcel;

Fig. 2 is the second position the cord having passed one way entirely around the parcel and about the parcel tie and at right angles thereto;

Fig. 3 is the third position after the cord has been passed both ways about the parcel and about the tie and is in position for exerting the stress for tightening the parcel;

Fig. 4 is a position after the parcel has been tightened and the cord being drawn into the clamp;

Fig. 5 is a perspective view of the parcel tied with the improved parcel tie;

Fig. 6 is a perspective view of the parcel tie member enlarged;

Fig. 7 is a top plan view of the parcel tie member showing the cord in tying position associated therewith but no parcel;

Fig. 8 is a longitudinal sectional view taken on line 8—8 of Fig. 7, and

Fig. 9 is a view of the tie member in edge elevation.

55 Like characters of reference designate cor-

responding parts throughout the several views.

The improved parcel tie which forms the subject matter of this application comprises a plate 10 having at one end an opening preferably provided with an eyelet 11 in which a cord 12 is secured in any approved manner as by tying as indicated at 13. At the end of the plate 10 opposite the eyelet 11 a thumb disk 14 is positioned, the utility of which will be readily apparent by examining Figs. 1 to 4 inclusive.

Midway the ends of the plates 10 a mutilated disk 15 is provided having a hub 16 spacing the disk away from the plate 10 a sufficient distance to permit the cord 12 to be wound about the hub 16 for the purpose of tightening. The mutilation of the disk 15 consists of a notch 17 formed in one side corresponding to one of the lateral sides of the plate 10. The disk 15 and hub 16 are secured to the plate 10 in any approved manner as by a rivet 18 having an enlarged head 19 and square in cross section.

Upon the rivet 18 a disk 20 is loosely and slidably mounted, such disk being provided with a sleeve hub 21, with a spring 22 disposed within the sleeve hub 21 and bearing at one end against the head 19 and at the other end against the disk 20 tending to move the said disk toward the disk 15, the said disk 20 with the spring 22 forming the clamp for the cord 12.

In operation the device is placed upon the parcel to be tied as indicated at Fig. 1 with the thumb of either hand engaging the thumb disk 14 and the other hand carrying the cord 12 about the parcel and about the hub 16 at right angles to the first run of the cord. In this second or right angular position the cord is again carried around the parcel as indicated at Fig. 2 to again engage about the hub 16 about which it is wound and the cord drawn in the reversed direction as indicated at Fig. 3. When the tightening has been accomplished the cord is again carried around the hub 16 in the same direction until it engages in the notch 17 when it passes above the disk 15 and between such disk 15 and clamp disk 20. It is wound about the rivet 18 between the clamp disk 20 and the disk 15 once or as many times as may be found desirable to effect the secure tying of the device or to dispose of the unnecessary lengths of cord.

To untie, of course, the reverse motion is all that is required and the device is ready to be placed upon another parcel.

What I claim is:—

- 5 A cord fastener comprising a plate adapted at one end for attachment to a piece of cord, and at its opposite end having a thumb rest, a stem projecting from the top face of the plate, a lower disk secured to the stem 10 and spaced above the plate to enable the

cord to be passed therebetween, a resilient clamping member on the stem above the lower disk to frictionally bind the inserted cord, and a slot in said lower disk whereby the cord may be shifted from between the 15 plate and disk to between the disk and clamping member.

In testimony whereof I affix my signature.

JEFFERSON E. GATES.
